DESIGN FOR A READING GLASS

Samuel E. Bouchard, Rochester, N. Y., assignor to
Bausch & Lomb Optical Company, Rochester,
N. Y., a corporation of New York

Application September 24, 1940, Serial No. 95,338

Term of patent 7 years

To all whom it may concern:

Be it known that I, Samuel E. Bouchard, a citizen of the United States and a resident of Rochester, county of Monroe and State of New York, have invented a new, original, and ornamental Design for a Reading Glass, of which the following is a specification, reference being had to the accompanying drawing, forming a part thereof.

Fig. 1 is a top plan view of the reading glass, showing my new design.

Fig. 2 is an end elevation thereof.

Fig. 3 is a sectional view taken on line 3—3 of Fig. 1.

I claim:

The ornamental design for a reading glass, substantially as shown.

SAMUEL E. BOUCHARD.
